UNITED STATES PATENT OFFICE.

WILLIAM C. BRIGGS, OF ELIZABETH, NEW JERSEY.

HOIST.

Application filed May 22, 1920. Serial No. 383,412.

To all whom it may concern:

Be it known that I, WILLIAM C. BRIGGS, a citizen of the United States, residing in Elizabeth, New Jersey, have invented Hoists, 5 of which the following is a specification.

My invention relates to that type of hoist whose mechanism is actuated by an electric motor and more particularly to hoists primarily designed to be operated by a manually actuated chain or rope.

One object of my invention is to provide a novel means for operatively connecting a hoist of the above type with an electric motor, which means shall be relatively simple 15 in construction as well as reliable in operation.

It is further desired to provide a novel mounting especially designed to support an electric motor upon the hoist which it is intended to operate;—the invention contemplating a novel form of unitary structure especially designed to insure the perfect alignment of such motor with its associated bearings and the gearing whereby power is transmitted to the hoist.

Another object of the invention is to provide a novel form of unit which shall include an electric motor with the necessary gearing, particularly adapted to be applied 30 to various types of hand hoists without material change except such alterations as may be required to fit it to hoist frames of the several types and sizes.

These objects and other advantageous ends 35 I attain as hereinafter set forth, reference being had to the accompanying drawings, in which,

Fig. 1 is a sectional elevation illustrating my invention as applied to a hand hoist;

40 Fig. 2 is a vertical section on the line 2—2, Fig. 1, further illustrating my invention; and

Fig. 3 is a perspective view of the driving unit constituting part of my invention.

45 In the above drawings 1 represents the frame work and enclosing casing of a geared hoist of the type commonly actuated by a hand-operated chain or rope which passes over a suitable sprocket or sheave 2 operatively connected to the mechanism of the hoist, the detail construction of which has no bearing upon the present invention, and is not illustrated. In accordance with my invention however, the element 2 has rigidly 50 and if desired, detachably fixed to it a ring

gear 3 whereby the hoist can be operated either by hand or by power.

In carrying out my invention I provide an electric motor 4 of suitable capacity and preferably of the enclosed type, whose armature shaft 7 or an extension of the same has mounted upon it a worm 11 meshing with a worm wheel 9 which is loosely mounted on a shaft 12 and driven by a friction element as a safe guard against 65 overload. This latter shaft also has fixed to it rigidly, a pinion 13 meshing with the ring gear 3 which as before noted is connected to the element whereby power is to be transmitted to the mechanism of the hoist. 70

Further in accordance with my invention, the head or end frame 5 of the electric motor is formed as part of an integral casting having portions 6 and 8 enclosing respectively the worm 11 and the worm wheel 9 and also 75 has an elongated tubular portion 10 enclosing the shaft 12. This latter portion provides or supports bearings 14 for carrying said shaft and its associated worm wheel 9 and pinion 13, and this portion 5 likewise 80 includes a structure 15 designed to form a support for the motor and one end of the armature shaft as well as serve as or support, the bearing for carrying the load and thrust of the worm 11. 85

The portion 10 of the integral structure 5-6-8- has projecting from it a pair of arms or brackets 16 designed to fit the casing 1 of the hoist to which the power unit above described is to be applied, it being obvious 90 that the shape and proportions of these parts may be widely varied without departing from my invention, to suit them to hoists of various forms and sizes.

With the above described arrangement of 95 parts it is obvious that without change other than to attach the ring gear 3 to the chain wheel 2, my power unit, consisting of the electric motor with the reduction gearing comprised by the worm 11 and worm 100 wheel 9, shaft 12 and pinion 13, may be quickly and conveniently applied to a hoist, it being especially noted that the arrangement as a whole is compact and its parts are so disposed as to require little if any 105 head space above the hoist in excess of that required by the suspending hook 17.

The motor may be controlled by any suitable means known to the art and may be utilized to actuate the hoist in the manner 110

and at a speed dependent upon the design of its gearing. It is to be understood that I do not limit myself to any particular form of safety clutch since the detail construction 5 of this device may be widely varied without departing from my invention. It is especially to be noted that by reason of the fact that the parts 5-6-8 and 10 are made in one integral structure, the perfect alignment of 10 the various power transmitting elements is insured, but in addition, the rapid and convenient installation of the device is made possible and its reliable and efficient operation is safe-guarded.

15 So far as my invention is concerned, it is immaterial whether or not the hand wheel 2 is used in connection with the gear 3 for transmitting power from the shaft 12 to the mechanism of the hoist, since my device is 20 applicable with equal advantage to hoists designed for hand operation as well as to those having no provision for a manually operated device such as a chain or rope.

I claim:—

25 1. A power unit for use with hand-operated hoists comprising a shaft; a gear on said shaft adapted for connection with the mechanism of the hoist; an electric motor; worm gearing connecting said shaft 30 and the armature shaft of the motor; with an integral casing structure adapted to carry said motor and including bearings for the said shaft and for the said armature shaft and having means for attaching said casing 35 to the body of the hoist.

2. A power unit for use with hand-operated hoists comprising an electric motor; a shaft; a gear on said shaft adapted for connection with the mechanism of the hoist; 40 a worm wheel on said shaft; a worm en-

gaging said worm wheel; a shaft for said worm; an integral casing structure having bearings for said shafts; means for supporting said motor in position for connection with said worm shaft; and means for attaching the casing to the body of the hoist. 45

3. A power unit for use with a hand operated hoist comprising a shaft, a gear on said shaft for connection with the mechanism of the hoist, an electric motor, worm 50 gearing connecting the armature shaft of said motor to said first shaft, a slip friction clutch connecting said worm gearing with the latter shaft, an integral casing structure adapted to carry said motor and including 55 bearings for said shafts, with means for attaching the casing to the body of a hoist.

4. A power unit for a hand operated hoist comprising an electric motor, worm gearing connected to the armature shaft of said 60 motor, a multiple disc friction clutch having one member connected to said worm gearing, a shaft connected to the other member of the clutch, gearing for connecting the shaft to the mechanism of a hoist, a sup- 65 porting structure for the motor including bearings for said shaft and said worm gearing, with means for attaching said casing to the body of a hoist.

5. A power unit for use with a hand op- 70 erated hoist comprising an integral casing including a structure for connection with the body of a hoist; bearings in said casing, a shaft in said bearing, a worm gearing in the casing, a slip friction clutch connecting 75 said worm gearing with said shaft, and an electric motor carried by the casing, said casing being formed to enclose and support the shaft, the gearing and the clutch.

WILLIAM C. BRIGGS.
